UNITED STATES PATENT OFFICE.

DAVID H. LENTZ, OF JOLIET, ILLINOIS, AND HENRY C. SHAW, OF PITTSBURG, PENNSYLVANIA, ASSIGNORS TO THE MCKENNA STEEL WORKING COMPANY, OF MILWAUKEE, WISCONSIN.

MACHINE FOR ROLLING RAILWAY-RAILS.

SPECIFICATION forming part of Letters Patent No. 625,403, dated May 23, 1899.

Application filed February 21, 1898. Serial No. 671,044. (No model.)

To all whom it may concern:

Be it known that we, DAVID H. LENTZ, residing at Joliet, in the county of Will and State of Illinois, and HENRY C. SHAW, residing at Pittsburg, in the county of Allegheny and State of Pennsylvania, citizens of the United States, have invented a certain new and useful Improvement in Machines for Rolling Railway-Rails, of which the following is a full, clear, concise, and exact description, reference being had to the accompanying drawings, forming a part of this specification.

Our invention relates to a machine for rolling railway-rails, and more particularly to a machine adapted to assist in the operation of rerolling or renewing old steel rails.

The machine of our invention was designed primarily to do the first work which is done upon the rail in such renewing process after it leaves the furnace and is intended to be placed immediately in front of the opening in the furnace and in addition to doing work upon the rail to perform the function of withdrawing a rail from any part of said furnace, so that we term the machine a "drawing-out roll."

It is desirable before work is had on the main rolls that the rail should be reduced to a uniform height and that the scale that has formed upon it while in the furnace should be removed.

In accordance with our invention a way is provided extending across the opening in the furnace, and a pair of standards, which carry the rolls, are adapted to be moved to and fro along said way. The rolls are comparatively short and have smooth surfaces throughout their operative length, and a guide is provided for directing a rail between said rolls to prevent lateral displacement of said rail while being worked. The lower roll supports the flange of the rail, while the upper roll engages with its head. Means are preferably provided for securing a vertical adjustment of the upper roll in order to vary the distance between said rolls to accommodate rails of different heights. To effect the rotation of the rolls, gear-wheels are provided upon the ends thereof, which mesh with pinions mounted to rotate with but movable longitudinally

upon driven shafts which extend as far as the roll-train is desired to travel. These shafts are provided with intermeshing gear-wheels at their ends, which cause the same to rotate at a uniform speed and in opposite directions, 55 said gear-wheels being driven by any suitable mechanism, preferably by a driving-belt wheel mounted upon the same shaft with one of them.

The effect of passing a rail between the two smooth rolls of the machine of our invention is to crush the head of the rail or buckle its web, or both, thereby reducing the rail to a uniform height at all points, in condition to be passed through the roughing-rolls. The 65 scale is also broken, so that it may be readily removed by scrapers. These results are had, moreover, without disturbing the original fish-ing-angles of the rail.

We will explain the details of construction 70 of our improved machine more particularly by reference to the accompanying drawings, in which—

Figure 1 is a front elevation of the rolling-machine embodying our invention. Fig. 2 is 75 a sectional view on line 2 2 of Fig. 1. Fig. 3 is a sectional view on line 3 3 of Fig. 1.

Similar parts are designated by similar letters of reference throughout the several figures.

The rolls *a b* are journaled to rotate in bearings *a' b'*, respectively, provided in the standards *c*. The roll *a* is provided upon one of its ends with a gear-wheel *a²*, and the roll *b* is likewise provided with a gear-wheel *b²*. Gear-wheels *a² b²* mesh with pinions *a³ b³*, respectively, which are adapted to be rotated to operate the rolls in a manner hereinafter to be described.

The standards *c* are supported upon the 90 way *d*, which extends across the opening in the furnace, and said standards are adapted to be moved along said way to bring the rolls *a b* opposite any portion of said opening. Guides *c² c³* are provided between the standards *c*, said guides being adapted to direct a rail as it is being passed between said rollers and prevent lateral displacement thereof. Rollers *c⁵ c⁶* are also provided in connection with said guides to facilitate its movement. 100

To effect the movement of said standards along said way, we preferably provide threaded bearings $c' c$ in the lower part of said standards, said bearings being engaged by a threaded shaft d' , extending along said way as far as the roll-train is desired to travel. Means for rotating said threaded shaft d' in either direction will be hereinafter described.

- The pinions $a^3 b^3$ are mounted to rotate with but are movable longitudinally upon the square shafts $e f$, respectively, which are journaled to rotate in bearings provided therefor in standards $g h$, mounted upon the ends of said way. Intermeshing gear-wheels $e' f'$ are provided upon the shafts $e f$, respectively, and upon an extension f^2 of the shaft f is mounted a driving-wheel f^3 , over which a driving-belt f^4 may be passed. Upon the rotation of said driving-wheel rotation will be imparted to the roll a through the medium of gear a^2 upon the end thereof, pinion a^3 , shaft e , gear-wheel e' , gear-wheel f' , and extension f^2 of the shaft f , upon which extension the driving-wheel is mounted. Likewise rotation at the same speed but in an opposite direction will be imparted to the roll b through the medium of gear-wheel b^2 and pinion b^3 , mounted upon the square shaft f , upon the extension f^2 whereof the driving-wheel is mounted.
- The threaded shaft d' is journaled to rotate in bearings $g' h'$, provided in the standards $g h$. A bevel gear-wheel d^2 is provided upon said shaft, said bevel gear-wheel meshing with bevel-pinions $d^3 d^4$ at either side thereof, said pinions being loosely mounted upon a common shaft i . Clutches $i' i^2$ are provided upon said shaft, said clutches when actuated being caused to engage with the bevel-pinions $d^3 d^4$, respectively, to cause said pinions to rotate with the shaft. An operating-lever i^3 is provided, which may be manipulated to cause one or the other of the clutches $i' i^2$ to engage with said pinions. The shaft i is journaled to rotate in bearings $k k$. A bevel gear-wheel l is mounted upon the shaft i , said bevel gear-wheel meshing with a bevel-pinion l' , provided upon the end of a short shaft m , said shaft being journaled to rotate in a bearing n . At the other end of said shaft m is provided a gear-wheel m' , which meshes with the gear-wheel f' , mounted upon the shaft f . By an inspection of Fig. 3 it will be understood that if the lever i^3 be manipulated to cause the clutch i' to engage with the pinion d^3 rotation in an opposite direction to that of the shaft f will be imparted to the threaded shaft d' through the medium of bevel-gear d^2 upon the end of said threaded shaft, pinion d^3 , shaft i , gear-wheel l , pinion l' , shaft m , gear-wheel m' , and gear-wheel f' upon said driving-shaft f , thus causing the roll-train to travel along the way d . In like manner if the operating-lever i^3 be manipulated to cause the clutch i^2 to engage with the pinion d^4 ro-

tation corresponding to the direction of rotation of said driving-shaft f will be imparted to the threaded shaft d' .

Adjusting-screws $o p$ are provided in the standards $c c$ for causing a vertical adjustment of the upper roll a , the rotation of said adjusting-screws being effected by an arrangement of bevel-gears actuated by a hand-wheel q , which construction is well known and requires no further description. The rolls $a b$ are preferably constantly driven, and by manipulation of the operating-lever i^3 the whole roll-train may be moved to and fro along the way d in a manner already described to bring the said roll-train opposite any part of the opening in said furnace, where-by a rail lying at any part of the furnace may be directed immediately between the rolls.

Having thus described our invention, what we claim as new, and desire to secure by Letters Patent, is—

1. The combination with a furnace, of a way extending across the opening thereof, a rail-rolling machine mounted to travel to and fro along said way in front of the furnace, said rail-rolling machine having a pair of cylindrical rolls with smooth surfaces for engaging the top and bottom only of the rail and adapted to bring the head and flange of the rail nearer together, guides for directing a rail between said rolls, other guides for preventing lateral displacement of the rail while it is being rolled, and means for moving the machine to and fro along said way in front of said furnace to receive a rail lying in any part of the opening of said furnace, substantially as described.

2. The combination with a furnace, of a way extending across the opening thereof, a rail-rolling machine mounted to travel to and fro along said way in front of the furnace, said rail-rolling machine having a pair of cylindrical rolls forming opposing smooth surfaces between which a heated rail may be passed, whereby the head and flange of such rail are brought nearer together during its passage between said rolls, guides for directing a rail between the rolls and for preventing lateral displacement of the rail while being rolled, and means for moving the machine to and fro along said way in front of said furnace to receive a rail lying in any part of the opening therein, substantially as described.

In witness whereof we hereunto subscribe our names in the presence of witnesses.
